Fig. 1

Fig. 2

Fig. 5

Fig. 1 is a front perspective view taken from the top and right end of a medical examination table embodying my new design, the left end being substantially plain;

Fig. 2 is a rear perspective view thereof;

Fig. 3 is an enlarged fragmentary front perspective view of the left end thereof;

Fig. 4 is an enlarged front elevational view of the drawer handle thereof;

Fig. 5 is a further enlarged vertical sectional view of the drawer handle thereof taken on line 5-5 of Fig. 4; and

Fig. 6 is an enlarged fragmentary top perspective view of the right end thereof with a portion of the table cover being broken away to disclose the appearance of the extension board.

The wood graining has been omitted from Figs. 3, 4 and 6 for convenience of illustration.

I claim:

The ornamental design for a medical examination table as shown and described.
